DESIGN.

—o—

A. B. CAMERON.
ORNAMENTAL PANEL.

No. 19,476.

Patented Dec. 10, 1889.

UNITED STATES PATENT OFFICE.

ALLAN B. CAMERON, OF WILLIAMSPORT, PENNSYLVANIA.

DESIGN FOR AN ORNAMENTAL PANEL.

SPECIFICATION forming part of Design No. 19,476, dated December 10, 1889.

Application filed November 12, 1889. Serial No. 330,080. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

- 5 My design relates to an ornamental configuration upon the surface of a panel.
- 10 My design shows a lenticular elevation A.

Beside this elevation and near each end thereof appear the groups of elevations B C D E and F G H I. My said design may be repeated, as shown.

15

I claim as my invention—

The design for an ornamental panel, substantially as herein shown and described.

ALLAN B. CAMERON.
